No 52,092, Patented Jan. 16, 1866

UNITED STATES PATENT OFFICE.

E. LAWRENCE TEVIS, OF PHILADELPHIA, PENNSYLVANIA.

CORN-SHELLER FOR TABLE USE.

Specification forming part of Letters Patent No. 52,092, dated January 16, 1866.

To all whom it may concern:

Be it known that I, E. LAWRENCE TEVIS, of Philadelphia, in the county of Philadelphia, State of Pennsylvania, have invented a new and Improved Corn-Shell for Table Use; and I do hereby declare that the following is a full and exact description thereof, reference being had to the accompanying drawings, and to the letters of reference marked thereon.

To enable others skilled in the art to make and use my invention, I will hereby describe its construction and operation.

The sheller, Fig. 1, is made of wood or any metal generally used for forks and spoons. The handle, entirely similar to that of a table-spoon or fork, is formed at point A into two branches, K and K', of well proportioned thickness and width, said branches supporting the saw-toothed blade D, which is set on them at a proper angle, of ninety degrees or about, with the plan of the branches K K'.

The way of using the sheller above described is as follows: The left hand holds the ear of corn with any ordinary table-fork, while the right hand scrapes the corn off the cob with the sheller above described, and shown in Fig. 2.

I am aware that many devices have been already invented and contrived for the making of instruments fitted for shelling and scraping corn-ears. I am also aware that toothed blades have been applied to the same use; but

What I claim as new, and desire to secure by Letters Patent, is—

The toothed blade D, in combination with branches K K' and handle H, using for that purpose any suitable metal or hard wood, or both combined, when constructed and operating as herein set forth and described.

In testimony that I claim the above I hereunto set my hand.

E. LAWRENCE TEVIS
